UNITED STATES PATENT OFFICE.

GEORGE W. WAITT, OF SAN FRANCISCO, CALIFORNIA, ASSIGNOR TO
BENJAMIN F. WAITT, TRUSTEE, OF SAME PLACE.

PIPE-WRENCH.

SPECIFICATION forming part of Letters Patent No. 592,031, dated October 19, 1897.

Application filed August 28, 1896. Serial No. 604,161. (No model.)

To all whom it may concern:

Be it known that I, GEORGE W. WAITT, a citizen of the United States, residing at San Francisco, in the county of San Francisco and State of California, have invented certain new and useful Improvements in Pipe-Wrenches; and I do hereby declare that the following is a full, clear, and exact description thereof.

My invention relates to pipe-wrenches of the class in which a sliding jaw is combined with a handle, and with a pivoted jaw, the pipe being seized between the two jaws.

My object is to make a simpler, stronger, and more effective wrench of this class, and further to provide a removable sliding toothed jaw, capable of being separately manufactured of tool-steel, if desired, and hence possessing the requisite hardness, to seize and penetrate iron pipe, while the body of the wrench can be made from cast-steel, of the requisite toughness and strength, but without the hardness and consequent brittleness which renders tool-steel undesirable for the body of such an implement. I have shown in the accompanying drawings what I consider the best embodiment of my invention to accomplish these objects, and have fully described such construction in this specification.

Figure 1 is a plan view of the wrench with the casing or handle broken away to show a partial longitudinal section. Fig. 2 is a side elevation of the same character. Fig. 3 is a cross-section through one of the jaws on the line $\alpha\alpha$ of Fig. 1.

A represents the shank or handle of the wrench, which is formed from separate plates of metal $a a' b b'$, and is rectangular in cross-section and hollow from end to end. At the operating or jaw end of the wrench the plates $b b'$ are widened, so as to afford an offset c , composed of the two projecting plates, between which is pivoted the jaw B, upon a pin d. This jaw is of a generally curvilinear form, and projects across and opposite the end of the handle. Its inner or bearing surface is preferably of angular shape, as shown, and may be toothed, if preferred, although this is not essential to the efficiency of the wrench. The plate a of the casing terminates at the base of the offset c in order that

room may be given for the enlarged end e of sliding jaw C. A separate flat plate f is set in the space between the projecting plates b , and forms the base of the recess which contains the jaw B, and is also a guide for the sliding jaw C.

The jaw B is pressed by a leaf-spring g , which lies in the recess flush with its edges and which tends to hold the jaw in its operative position, but yields to permit the pipe to be seized.

The jaw C is preferably made from tool-steel, and has a beveled end, adapted to project from the handle and seize the pipe in connection with the pivoted jaw. This jaw C has an enlarged end or head, as before stated, formed by an inclined shoulder h , the latter bearing against the similarly-inclined end i of the plate a , by which its motion in one direction is limited. The inner end of the shank of the jaw is pivoted by a pin k between ears formed upon a long threaded nut l , which travels upon the screw m . The screw has a smooth cylindrical end portion n projecting through the end of the handle, where a bearing o is provided for it, and is provided with an operating-handle p .

The sliding jaw, nut, and screw-rod are all carried within the wrench handle or casing, and are all in the same longitudinal line, so that the power is applied directly upon that line, which is the most effective way, while at the same time all the operative parts are held and supported by and within the casing. The wrench is consequently much stronger and more effective than those in which the sliding jaw is guided in an offset to one side of the handle, for the two reasons just mentioned.

By pivoting the jaw C to its operating-nut I prevent any binding in the handle; but such pivoting can only be done, without sacrificing strength, when the jaw is firmly guided and supported by a long bearing within the handle.

Having thus described my invention, what I claim as new, and desire to secure by Letters Patent, is—

1. In a pipe-wrench, a hollow handle, a jaw pivoted thereto, a sliding jaw guided within and by the handle, a screw-rod, having a bear-

ing within the handle, and a nut traveling upon said rod, and hinged to said sliding jaw, substantially as described.

2. In a pipe-wrench, a handle, hollow, and open at both ends, a jaw pivoted in an offset of said handle, a jaw sliding and guided in said handle, and movable through one of its open ends, a threaded nut within the handle, connected to said jaw, a screw-rod engaging 5 with said nut, and projecting through the opposite open end, and an operating-handle on the end of said rod, all substantially as described.

3. In a wrench, and in combination, a handle composed of plates *a*, *a'*, *b*, *b'*, said plates 10 *a*, *a'*, having projections *c*, a jaw *B*, hinged in

the recess formed by said projections, a jaw *C* sliding in the handle, and having a shoulder, for which said plate *a* is a stop, a separate plate forming a base or bottom to said 20 recess and a guide for said sliding jaw, and means contained within the handle for operating said sliding jaw, substantially as described.

In testimony whereof I have affixed my signature, in presence of two witnesses, this 21st day of August, 1896.

GEO. W. WAITT.
